Primary Examiner — Sheryl Lane(74) *Attorney, Agent, or Firm* — McHale & Slavin, P.A.(57) **CLAIM**

The ornamental design for a self-watering planter, as shown and described.

DESCRIPTION

FIG. 1 is a top right perspective view of the self-watering planter of the present invention;

FIG. 2 is a front view thereof;

FIG. 3 is a rear view thereof;

FIG. 4 is a right side view thereof;

FIG. 5 is a left side view thereof;

FIG. 6 is a bottom view thereof;

FIG. 7 is a top view thereof; and,

FIG. 8 is a rear top right perspective view thereof.

The portions of the self-watering planter illustrated in broken lines form no part of the claimed design.

1 Claim, 8 Drawing Sheets(56)
